UNITED STATES PATENT OFFICE.

JOSEPH BUTCHER, OF JERSEY CITY, NEW JERSEY.

THERMOSTAT.

SPECIFICATION forming part of Letters Patent No. 631,278, dated August 22, 1899.

Application filed October 22, 1898. Serial No. 694,248. (No model.)

To all whom it may concern:

Be it known that I, JOSEPH BUTCHER, a citizen of the United States, residing at Jersey City, Hudson county, New Jersey, have invented certain new and useful Improvements in Thermostats, of which the following is a specification.

This invention relates to the class of thermostats such as those employed in heat-regulating mechanisms controlled or operated electrically.

The object of the invention is to provide a simple, inexpensive, and very sensitive thermostat adapted to act positively under very slight changes in temperature.

In the accompanying drawings, which illustrate an embodiment of the invention, Figure 1 is a face view or front elevation of the thermostat. Fig. 2 is a similar view, but with the face plate omitted. Fig. 3 is a view of the back or under side of the thermostat. Fig. 4 is a longitudinal axial section of the thermostat. Figs. 5, 6, and 7 are transverse sections in the respective planes indicated by lines x^5 , x^6 , and x^7 in Fig. 1. Fig. 8 shows the thermal element detached in perspective. Fig. 9 is a general diagrammatic view on a small scale, illustrating one application of the thermostat to the regulation of the heat of a furnace.

30 In the general view Fig. 9, T represents the thermostat as a whole; F, a furnace to supply heat; M, an electric motor adapted to control the dampers of the furnace F, and B is a battery which supplies electric energy to the motor M.

This invention has to do with the thermostat T, the purpose of which is to control the operation of the motor M.

In the thermostat as illustrated in Figs. 1 to 7, 1 is a base-piece, which will be by preference of wood, compressed fiber, or the like. The preferred form of this base-piece is fully illustrated. It is elongated and has a longitudinal recess 2, Fig. 2, in its face to receive the thermal element 3. This element is composed, Fig. 8, of a strip of zinc z and a strip of glass g , the two being cemented together face to face. The strip z has at one end a flange-piece 3^a , whereby the element is adapted to be fixed, and at its free end it has by preference a bit of platinum wire 3^b , set transversely to form contact-points. This element 3 is

mounted in the recess 2 of the base on the free end of a spring-tongue 4, which will be by preference formed integrally with the base-piece 1, said tongue having a little room for lateral play at its free end, on which the thermostatic element 3 is fixed. The free end of the element 3 is situated between two contact-screws 5^a and 5^b , set in the base-piece and forming terminals of conductors w and x , respectively, leading directly to the motor M, as seen in Fig. 8. On the free end of the tongue 4 and conveniently formed on the flange-piece 3^a of the element 3 is a pin or projection 6, which engages a recess, Fig. 2, in a rotatively-mounted post or arbor 7, set in the base-piece 1. By rotating this post to the right or left the tongue 4 may be deflected a little at its free end to the right or left, thus carrying the fixed end of the member 3 with it and deflecting the free end of the latter in the opposite direction.

Mounted on the base-piece 1 is a face-plate 8, on which is marked a scale or series of 75 graduations s , indicating degrees and curved so as to be concentric to the post 7, and to the latter is fixed a pointer p , which traverses the scale when the post 7 is turned.

Now if the post or arbor 7 be turned to the left, say, to "80°" on the scale s , as seen in Figs. 1 and 2, the free end of the member 3 will be moved over into contact with the contact-screw 5^a , which may be called the "closing-contact," as it causes the current to flow 85 through the motor M and close the dampers of the furnace F. This operation will cause a rise in temperature, and the zinc strip z of the element 3, which has a much greater coefficient of expansion than that of the glass 90 strip g , will expand lengthwise, and it follows that the member 3 will be flexed to such an extent that when the temperature reaches 80° its extremity will contact with the other contact-screw 5^b , which may be called the 95 "opening-contact," as this contact closes the circuit through the motor M and causes the latter to open the dampers of the furnace F.

When the free end of the thermostatic member 3 is in electrical contact with either of the contact-screws 5^a or 5^b , the current flows from the battery B by a conductor v to a switch-post 9, Figs. 3 and 4, thence through a switch-arm 10 to a post 11, thence by a con-

ductor v' to a supporting-post 8^a of the face-plate 8 , thence through said plate to a supporting-post 8^b at the other end of said plate and a conductor v^2 to the zinc z , thence through 5 said zinc to the contact-screw 5^a or 5^b , thence to the conductor w or x to the motor M , and thence from the said motor by a conductor u , Fig. 9, to the other pole of the battery B . These posts form, with the contact-screws, the 10 terminals of a branched circuit leading to the motor M .

In the operation of this thermostat the user may place it in any room wherein the temperature is to be regulated, and he may set 15 the pointer p to any degree marked on the scale s . The contact-screws 5^a and 5^b screw transversely through metal posts 5^c and 5^d , set in the base-piece, so that the contacts 5^a and 5^b may be adjusted with great nicety with 20 reference to the contacts at the free end of the member 3 . As the flexing of the tongue 4, which will be stiff and springy, requires some little force, a friction-producing device is employed to hold the arbor 7 in position after 25 it is turned, and this device is best illustrated in Fig. 7. The arbor has at the bottom a journal which occupies a bearing in the base-piece 1, a rather thick body in which is formed the recess to engage the projection 30 6 on the member 3, an elongated neck which projects up through the face-plate 8 , and a removable milled head which fits on said neck. The pointer p extends through the lower part of said milled head and the arbor 7 and is held 35 in place firmly by a set screw 7^a , driven down into the top of the arbor 7. Under the face-plate 8 and bearing upwardly at its ends against the same is a leaf-spring 12, through the center of which the neck of the arbor 40 passes, said spring being seated on a shoulder on the arbor. This spring being compressed between the face-plate and the said shoulder, friction is created, which resists to the proper degree the rotation of the arbor and holds it 45 where it is set.

If the operator desires, he may turn the arm of the switch 10 off from the post 11, and thus open the circuit, or he may turn it to rest upon either of the posts 5^c and 5^d , whereby 50 he may keep the dampers open or closed. For example, if he shifts the arm of the switch to the post 5^c the dampers will be held open and if to the post 5^d they will be held closed. The switch 10 is therefore capable of performing 55 several functions—namely, to connect the thermostat with a battery and motor, to break the circuit from the battery to the motor, to close a circuit to keep the dampers closed, and to close a circuit to keep the dampers open. 60 The normal temperature, a change from which causes the thermostat to act, may be taken at any desired degree and the pointer p set to that degree on the scale s , when the tongue 4 is in its normal position and not under strain or tension. In the drawings the 65 normal is supposed to be 70° , and in Figs. 1 and 2 the pointer is set to " 80° ," so that the

temperature will reach that point before the dampers are opened.

The current is described as flowing through 70 the wire v^2 , Fig. 2; but this wire may be considered merely as a precautionary conductor, as the current will flow as well from the plate 8 to the arbor 7 and thence to the zinc z through the projection 6. Indeed, it is only 75 necessary that the zinc z shall be connected electrically with the post 11, and it is not important to my invention how this connection is made.

Zinc and glass are employed in forming the 80 thermostatic element for the reason that they are solids capable of being made into strong and rigid strips. They do not corrode, rust, or deteriorate in use even when employed for an indefinite period. They are very cheap 85 and easily obtainable, and the difference in their coefficients of expansion is so great as to render the thermostat very sensitive. The contact-screws 5^a and 5^b enable the movement of the free end of the zinc z to be regulated 90 very nicely, the movement allowed corresponding, by preference, to 5° of temperature, although it may be made to work down to 1° ; but the range of 5° is preferred, as it obviates starting the dampers by the temporary opening 95 of windows or doors when the thermostat is employed to control the dampers of a heating apparatus.

The motor M has not been illustrated herein except diagrammatically, as it forms no 100 part of this invention, and motors of this general character and capable of being used in connection with the thermostat described are known. It need only be said that the motor may comprise an electromagnet with a 105 vibrating armature which actuates a pawl, this latter imparting rotation to a ratchet-wheel which operates the dampers. When the damper is fully closed, the closing branch of the circuit will be broken at the motor, and when the temperature acts on the thermostat to close the opening branch of the circuit the motor will be set in motion to open the damper. When this opening is effected, the opening branch of the circuit will be broken at the 115 motor.

In the drawings the element 3 is represented as wrapped with wire, but this is not essential at all. In cementing the zinc and glass strips together it is convenient to wrap them 120 with a fine wire until the cement hardens or sets, and this wire is not ordinarily removed, although it might be, as the cement, which will be by preference tough and somewhat elastic, will hold the strips firmly together 125 face to face. The zinc strip will project at both ends of the element beyond the strip of glass. The purpose of this is to provide metallic contact at both ends of the element and to avoid the necessity of drilling the glass. 130 The member 3 extends back over the tongue and is out of contact with the latter along its free portion. The engagement of the projection 6 with the recess in the arbor 7 is a coup-

ling or connection substantially similar to a tooth of a rack engaging between the teeth of a pinion; but the rotatory movement of the arbor is so limited that only one tooth and 5 recess are needed.

Having thus described my invention, I claim—

1. A thermostat having its element 3 composed of a strip of glass *g*, and a strip of zinc *z*, secured together face to face, substantially as set forth.

2. A thermostat having its element 3 composed of a strip of glass and a strip of zinc cemented together, face to face, the strip of zinc extending beyond the glass at both ends, substantially as set forth.

3. A thermostat having a base provided with a spring-tongue, a thermostatic element secured at one end to the free end of said tongue and extending back over said tongue whereby the free end of the element is adjacent to the fixed end of the tongue, electrical contact-terminals adjacent to the free end of said element, and means for moving the free 25 end of said tongue laterally, substantially as set forth.

4. A thermostat having a base 1, provided with an integral spring-tongue 4, a thermo-

static element 3, fixed at one end to the free end of said tongue and extending back over 30 the same, electrical contact-terminals adjacent to the free end of said element, and means for moving the free ends of said tongue 4 laterally, substantially as set forth.

5. A thermostat having a base-piece provided with a spring-tongue, a thermostatic element secured at one end to the free end of said tongue and extending back over said tongue, electrical terminal contacts on said base adjacent to the free end of said element, 35 a face-plate having a scale *s*, and mounted on said base-piece, an arbor 7, mounted in the base-piece adjacent to the free end of said tongue and carrying a pointer *p* adapted to traverse said scale when the arbor is turned, 40 and means coupling said arbor and the free end of said tongue whereby the tongue is moved laterally by the rotation of the arbor, substantially as set forth.

In witness whereof I have hereunto signed 50 my name, this 19th day of July, 1898, in the presence of two subscribing witnesses.

JOSEPH BUTCHER.
